UNITED STATES PATENT OFFICE

135,602

DESIGN FOR A TEXTILE FABRIC

Siegfried Klauber, New York, N. Y.

Application February 22, 1943, Serial No. 109,604

Term of patent 3½ years

To all whom it may concern:

Be it known that I, Siegfried Klauber, a citizen of no country, but who has declared his intentions of becoming a citizen of the United States of America, and a resident of New York city, county of New York, State of New York, have invented a new, original, and ornamental Design for a Textile Fabric, of which the following is a specification, reference being had to the accompanying drawing, forming part thereof, wherein, the figure of the drawing is a plan view of a piece of textile fabric showing my new design. A full width of the textile fabric is shown. The dot and dash lines indicate the edges beyond which the design unit disclosed is repeated in regular succession.

I claim:

The ornamental design for a textile fabric, substantially as shown and described.

SIEGFRIED KLAUBER.
